UNITED STATES PATENT OFFICE

132,904

DESIGN FOR A BOTTLE DISPLAY UNIT OR SIMILAR ARTICLE

John D. Buckingham, Chicago, Ill., assignor to Lucien Lelong, Inc., Chicago, Ill., a corporation of Illinois

Application April 25, 1942, Serial No. 106,700

Term of patent 14 years

To all whom it may concern:

Be it known that I, John D. Buckingham, a citizen of the United States and a resident of the city of Chicago, in the county of Cook and State of Illinois, have invented a new, original, and ornamental Design for a Bottle Display Unit or Similar Article, of which the following is a specification, reference being had to the accompanying drawing, forming a part thereof.

On the drawing:

I claim:

The ornamental design for a bottle display unit or similar article, as shown.

JOHN D. BUCKINGHAM.
